CLAIM

The ornamental design for a curved detailing tool, as shown and described.

DESCRIPTION

FIG. 1 is a perspective view of the curved detailing tool showing my new design;

FIG. 2 is an alternative perspective view thereof;

FIG. 3 is an alternative perspective view thereof;

FIG. 4 is an alternative perspective view thereof;

FIG. 5 is an alternative perspective view thereof;

FIG. 6 is a top view thereof;

FIG. 7 is a front view thereof;

FIG. 8 is a bottom view thereof;

FIG. 9 is a rear view thereof;

FIG. 10 is a left side view thereof; and,

FIG. 11 is a right side view thereof.

The broken lines depict portions of the curved detailing tool in which the design is embodied that are not considered part of the claimed design.

1 Claim, 6 Drawing Sheets
